UNITED STATES PATENT OFFICE.

RALPH ROSE SANDFORD, OF NEW LONDON, OHIO, ASSIGNOR OF ONE-HALF TO THE NEW LONDON MFG. CO., OF NEW LONDON, OHIO.

SEAM FOR RAIN-COATS.

1,268,059.

Specification of Letters Patent. Patented May 28, 1918.

Application filed October 31, 1917. Serial No. 199,459.

To all whom it may concern:

Be it known that I, RALPH R. SANDFORD, a citizen of the United States, and a resident of New London, in the county of Huron and 5 State of Ohio, have invented a new and Improved Seam for Rain-Coats, of which the following is a full, clear, and exact description.

The object of the invention is to provide a 10 new and improved seam for rain coats and other similar waterproof garments and arranged to prevent the seam from accidentally opening and to render the seam watertight.

15 In order to accomplish the desired result, use is made of a strip of fabric material overlying the overlapping seam sides of the garment, an adhesive substance between the contacting surfaces of the said seam 20 sides and the said strip, and stitches connecting the sides of the said strip with the seam sides, the said adhesive substance filling the stitch holes.

A practical embodiment of the invention 25 is represented in the accompanying drawings forming a part of this specification, in which similar characters of reference indicate corresponding parts in both views.

Figure 1 is a rear elevation of a rain coat 30 provided with the improved seams; and Fig. 2 is an enlarged cross section of the same on the line 2—2 of Fig. 1.

The material of which the body of the rain coat is made is preferably of two waterproof fabrics fastened together in the usual manner by an adhesive substance, and the coat is made in the usual parts connected with each other by seams 10, each of which has overlapping seam sides 11 and 12, of 35 which the outermost seam side 12 is doubled up, as plainly shown in Fig. 2, and is connected with the other seam side 11 by stitches 13. Each seam 10 is overlaid at the inner face of the garment body by a strip 40 45 of fabric material and preferably made double, that is, of the same two fabric materials of which the body of the garment is made. One side edge 16 of the strip 15 is doubled under and the other side edge 17 is provided with a binding 18, and the contacting 50 faces of the strip 15 and the corresponding seam sides 11 and 12 are connected with each other by an adhesive substance 20, such as cement. After the strip 15 is fastened

in place by the adhesive substance 20 and 55 while the latter is still in plastic condition the side edges of the strip 15 are fastened to the seam sides by stitches 25, 26, of which the stitches 25 pass through the doubled-up edge 16, and the stitches 26 pass through the 60 edge 17 and its binding 18, as plainly indicated in Fig. 2. Now owing to the fact that the adhesive substance 20 is still in plastic condition it is evident that the stitch holes formed by the needle are filled with some 65 of the adhesive substance 20 thus rendering the stitch holes waterproof.

In rain coats as heretofore made the seam strips were simply fastened to the seam sides by an adhesive substance but such strips 70 were liable to become loose with the wear and tear of the garment and the seams become correspondingly open. With the improvement above described the seam strip is securely fastened in place not only by 75 the adhesive substance but also by the rows of stitches 25 and 26, and in addition the stitch holes formed during the sewing operation are filled with the adhesive substance, thus rendering the stitch holes as well as 80 the seam completely waterproof. A seam made in the manner described is exceedingly strong and durable and is not liable to open up even if the garment is subjected to considerable strain.

Having thus described my invention, I 85 claim as new and desire to secure by Letters Patent:—

1. A waterproof garment having its body provided with overlapping seam sides, the 90 outer seam side being doubled up and the doubled up portion stitched to the inner seam side at a distance from its edge, a strip formed of two fabrics fastened together and of the same material as the said body fabric, 95 the strip overlying the said overlapping seam sides on the inner face of the garment, an adhesive substance fastening the said seam strip to the said seam sides, and stitches fastening the margins of the strip 100 to the seam sides.

2. In a waterproof garment, a seam comprising overlapping seam sides, a seam strip of fabric material overlying the said overlapping seam sides on the inner face of the 105 garment, an adhesive substance between the contacting surfaces of the said seam sides and the said strip, and stitches connecting

the sides of the said strip with the seam sides, the said adhesive substance filling the stitch holes.

3. In a waterproof garment, a seam comprising overlapping seam sides, a seam strip of fabric material overlying the said overlapping seam sides, the said seam strip having one edge tucked under and the other

edge provided with a binding, an adhesive substance between the contacting surfaces 10 of the said seam sides and the said strip, and stitches connecting the said seam sides with the tucked under edge and the said binding edge, the said cement filling the stitch holes.

RALPH ROSE SANDFORD.
